ATTORNEY.

UNITED STATES PATENT OFFICE.

JAMES A. CARR, OF CAMDEN, NEW JERSEY.

FASTENING FOR WATER-CONDUCTORS.

SPECIFICATION forming part of Letters Patent No. 352,805, dated November 16, 1886.

Application filed January 7, 1886. Serial No. 187,936. (No model.)

To all whom it may concern:

Be it known that I, JAMES A. CARR, a citizen of the United States, residing in the city and county of Camden, State of New Jersey, have 5 invented a new and useful Improvement in Fastenings for Water-Conductors, which improvement is fully set forth in the following specification and accompanying drawings, in which—

10 Figure 1 represents a partial side elevation and partial vertical section of a fastening for water-conductors embodying my invention. Fig. 2 represents a front view thereof. Fig. 3 represents a perspective view of a detached portion.

15 Similar letters of reference indicate corresponding parts in the several figures.

20 My invention consists of a device for fastening a water-conductor to a brick or stone wall, so constructed that the pin employed may be readily driven into the wall between the bricks or stone.

25 Referring to the drawings, A represents a plate or strap formed of metal, one end whereof is formed with openings B, whereby it may be riveted to the water conductor, pipe, or spout C. In the plate is a longitudinally-extending slot, D, the opposite side walls of which are serrated, as at E, the teeth facing each 30 other; but, if desired, they may be bent outwardly, as shown by dotted lines, Fig. 1.

35 F represents a pin, which is adapted to be passed through the slot D and driven into the wall of the building to which the conductor is attached.

40 It will be seen that, owing to the slot D, the pin may be driven into a brick or stone wall between the bricks or stones thereof, as may be most convenient to reach, and thus the fastening is adjustable to different sizes of bricks and stones and the location of the mortar be-

tween the same, the lines of mortar being visible through the slot, a reliable and serviceable device thus being presented. Owing to the serrations of the slot, as the pin is passed 45 through the same between coincident teeth, the plate is sustained on the pin, and thus the plate and conductor are prevented from dropping.

50 Outward displacement of the plate is prevented by the head of the pin, which overlaps the walls of the slot, as shown in Fig. 2.

55 In lieu of securing the conductor to the plate by rivets, it may be accomplished by soldering or other fastenings.

60 The teeth or serrations of the slot are shown pointed, but not necessarily so, as they may be rounded or other shape, and the slot need not be continuous, in which case it will possess greater strength.

65 For corrugated pipe the upper end of the plate is bent out, so that the conductor may set flush against the wall.

Having thus described my invention, what I claim as new, and desire to secure by Letters 65 Patent, is—

70 1. A fastening for a water-conductor, consisting of a plate having a slot, the edges thereof being serrated, substantially as and for the purpose set forth.

75 2. The plate A, having openings B, and slot D, with serrated edges E, in combination with the pin F, adapted to enter said slot, all substantially as described.

3. The plate A, having a slot with serrated 75 walls, the upper part of the plate being set out, substantially as described.

JAMES A. CARR.
